John H. Banning,
His Attorney.

UNITED STATES PATENT OFFICE.

JORDAN WEGMAN, OF CREVE COUER, MISSOURI.

LIQUID-FUEL BURNER.

1,420,003.

Specification of Letters Patent. Patented June 20, 1922.

Application filed May 2, 1921. Serial No. 466,141.

To all whom it may concern:

Be it known that I, JORDAN WEGMAN, a citizen of the United States, and residing at Creve Couer, St. Louis County, Missouri, have invented the new and useful Improvement in Liquid-Fuel Burners, of which the following is a specification.

This invention relates to oil burners and more particularly to that type of oil burner 10 in which a wick is employed to feed the fuel to the flame such as is used in oil stoves.

The ordinary oil burner of this type usually has an oil reservoir into which the wick 15 is adapted to dip and which is fed by a supply pipe from the main oil tank. It is desirable in this type of burner to have the oil reservoir into which the wick dips as small as possible so as to avoid storing a large quantity of fuel in the burner, 20 since such fuel is liable to cause a great fire risk.

The oil reservoir on this type of burner is usually constructed to have small capacity, and since a cylindrical wick is used, 25 this means that the reservoir usually takes the form of a double-walled cylindrical container with just enough space between the inner and outer walls to accommodate the 30 movement of the wick and to form a small reservoir for fuel. In this type of construction, the oil reservoir is not accessible on the inside for cleaning. As it often happens that burners of this type are allowed to be 35 come clogged with dirt or with materials spilled during cooking operations, which are liable upon cooling to become hard, it is very important to have such burners easily accessible on the inside and outside for 40 thorough cleaning.

One of the objects of this invention, therefore, is to provide a burner of this type which shall be capable of disassembly in such a way as to render it easily accessible 45 inside and outside for cleaning.

Another object of this invention is to provide such a burner having a fuel reservoir of limited capacity which at the same time may be constructed and arranged so 50 that upon disassembly, ample room is provided for easy access into the interior thereof.

Further objects will appear from the detail description taken in connection with the accompanying drawing, in which:

Figure 1 is a cross-sectional view of a burner embodying this invention; and

Figure 2 is a partial sectional view showing another embodiment of this invention.

Referring to the accompanying drawing, 60 the burner comprises a chimney 1 within which are arranged perforated cylindrical tubes 2 and 3 adapted to provide a space therebetween for the flame to travel, the perforations providing access for air to 65 the flame from within and without. In the interior of the tube 3 is arranged a distributor 4 in which the air rising through the draft tube is dispersed to the sides of the tube 3. The tubes 2 and 3 and the 70 chimney 1 are supported by a spider 5 mounted on a vertical rod 6 by means of which they may be raised and lowered. These parts may all be of any well known construction.

The tube 2 rests upon a flange 7 on the wick tube 8. This tube is of special construction and is provided with an outer cylindrical wall 9 and an inner cylindrical wall 10. These may be formed of one piece 80 of metal or they may be joined at the bottom by a plate 11 making tight joints so as to provide a fuel reservoir in the annular space between the walls 9 and 10. The walls 9 and 10 are spaced from one another and 85 the wall 10 terminates at a lower level than the wall 9 so that ample space may be left between the upper edges of the two walls, for access to the interior of the reservoir.

In order to reduce the fuel capacity of 90 the reservoir, a filler 12 is provided to occupy a major part of the interior space thereof. This filler is constructed with an exterior cylindrical wall 13 and an interior wall 14 joined by a bottom plate 15, which 95 construction may be similar to that of the wick tube 8. The filler may be closed at the top by a horizontal plate 16. All joints should be tight so as to prevent leakage of fuel into the interior of the filler. The exterior wall 13 of the filler may be provided with a smooth unbroken surface over which the wick 17 is adapted to move for adjustment of the flame. The wick may be

provided with the usual perforated tube 18 attached thereto and adapted to engage the adjusting wheel 19 whereby it may be raised or lowered for adjusting the flame. 5 An attachment 20 is provided for connecting the reservoir with the fuel supply. The interior wall 10 of the wick tube may be provided at its upper edge with threads 21 or any other suitable attaching means and 10 the interior wall 14 of the filler may be provided with similar attaching means adapted to engage the means 21 so that the filler when inserted into the reservoir may be securely attached to the wick tube. The 15 wall 14 may be provided with a spider 22 attached thereto and carrying a guide-tube 23 through which the rod 6 may move up and down for raising and lowering the chimney 1. The rod 6 is also usually provided with an offset 24 adapted when the 20 rod is rotated to engage a rest 25 so as to hold the chimney in a raised position.

In the embodiment shown in Figure 2 the wick tube 8 has its interior wall 10 arranged 25 inside of the wick 17 which is adapted to move thereover during adjustment. In this case the exterior wall 9 terminates at a lower level than the interior wall so as to provide a wide mouth for the reservoir to insure easy 30 accessibility. The filler 12 in this case is arranged outside of the wick and carries on its interior wall 14 the wick adjusting device 19. In this case the securing means 21 are provided at the upper edge of the exterior wall 9 of the reservoir and are engaged by similar securing means mounted on the exterior of the filler as shown in Figure 2. The spider 22 carrying the guide-tube 23 is mounted on the interior wall 10 of the 40 reservoir.

It will be seen that this invention accomplishes its objects. A wick tube is provided which is adapted to form a fuel reservoir having its interior and exterior walls spaced 45 from one another so as to provide accessibility and the excess fuel capacity so provided is then eliminated by introducing a filler. The interior wall of the wick tube provides an unobstructed draft tube to supply an ample quantity of air to the flame. If the burners should become clogged, it is only necessary to remove the filler after 50 which all interior parts are easily accessible and all foreign matter may easily be cleaned 55 out.

It is obvious that various changes may be made in details of construction without departing from the spirit of this invention; it is, therefore, to be understood that this 60 invention is not to be limited to the specific details shown and described.

Having thus described the invention, what is claimed is:

1. In a liquid fuel burner having a wick, 65 an enlarged wick tube adapted to form a

fuel reservoir, and a filler for said tube adapted to reduce the capacity of said reservoir.

2. In a liquid fuel burner having a wick, 70 an enlarged wick tube adapted to form a fuel reservoir, and having a draft tube therewithin, and a filler for said tube adapted to reduce the capacity of said reservoir.

3. In a liquid fuel burner having a wick, 75 an enlarged wick tube adapted to form a fuel reservoir, and a filler for said tube adapted to reduce the capacity of said reservoir, and adapted for removal to permit access to said wick tube.

4. In a liquid fuel burner having a wick, 80 an enlarged wick tube adapted to form a fuel reservoir, and a filler for said tube adapted to reduce the capacity of said reservoir, and adapted for removal to permit access to said reservoir.

5. In a liquid fuel burner having a wick, 85 an enlarged fuel reservoir into which the wick is adapted to extend, and a filler for said reservoir adapted to reduce the fuel capacity thereof.

6. In a liquid fuel burner having a wick, 90 an enlarged fuel reservoir into which the wick is adapted to extend, and a filler for said reservoir adapted to reduce the fuel capacity thereof, said filler being removable 95 to permit access to said reservoir.

7. In a liquid fuel burner having a wick, 100 an enlarged fuel reservoir into which the wick is adapted to extend, said reservoir having an inner and an outer wall, one of said walls terminating below the other, and a filler for said reservoir adapted to reduce the fuel capacity thereof.

8. In a liquid fuel burner having a wick, 105 an enlarged fuel reservoir into which the wick is adapted to extend, said reservoir having an inner and an outer wall, one of said walls terminating below the other, a filler for said reservoir adapted to reduce the fuel capacity thereof, and means for removably mounting said filler on said lower wall.

9. In a liquid fuel burner having a wick, 115 an enlarged fuel reservoir into which the wick is adapted to extend, said reservoir having an inner and an outer wall, one of said walls terminating below the other, a filler for said reservoir adapted to reduce the fuel capacity thereof, and a connection at the terminus of said lower wall for removably mounting said filler thereon.

10. In a liquid fuel burner having a wick, 120 an enlarged fuel reservoir into which the wick is adapted to extend, said reservoir being provided with inner and outer walls 125 having spaced upper termini, and a filler for said reservoir adapted to reduce the fuel capacity thereof.

11. In a liquid fuel burner having a wick, 130 a wick tube adapted to form a fuel reservoir,

and a removable spacer adapted to space the wick from the wall of said tube.

12. In a liquid fuel burner having a wick, a wick tube adapted to form a fuel reservoir, and a removable spacer between the wick and the wall of said reservoir.

13. In a liquid fuel burner having a wick,

a wick tube adapted to form a fuel reservoir, and a spacer between the wick and the wall of said tube, adapted for removal with the wick.

In testimony whereof I affix my signature this 20th day of April, 1921.

JORDAN WEGMAN.
